UNITED STATES PATENT OFFICE.

ERNEST J. FLATHER, OF NASHUA, NEW HAMPSHIRE.

INDEXING MECHANISM.

No. 874,754.

Specification of Letters Patent.

Patented Dec. 24, 1907.

Application filed January 10, 1906. Serial No. 295,468.

To all whom it may concern:

Be it known that I, ERNEST J. FLATHER, of Nashua, in the county of Hillsborough and State of New Hampshire, have invented certain new and useful Improvements in Indexing Mechanisms, of which the following is a specification.

This invention relates to gear cutting machines and has for its object to provide such a machine with improved mechanism for automatically indexing or feeding a gear blank after each operation of the cutting mechanism into position for making a new cut, which mechanism will be set in operation by the cutter carriage, or other moving part of the machine, after a cut has been completed, and will be automatically stopped after the blank has been fed the requisite amount.

Other objects are to obtain a mechanism which is relatively simple, easy to stop and start, certain in operation, and capable of fine and quick adjustments to secure any desired spacing of teeth.

The construction and arrangement of this mechanism are the same in most details as the indexing mechanism shown and described in my co-pending application Serial No. 213,070, filed June 18, 1904, for gear-cutting machine, the present application containing matter divided from that case, together with new and improved features.

On the accompanying drawings,—Figure 1 represents an end elevation and partial section of a gear-cutting machine equipped with my improved blank-indexing mechanism. Fig. 2 represents a side elevation of the indexing mechanism and a portion of the cutter-operating mechanism, parts being removed for clearness. Fig. 3 represents a top plan view of the driving and indexing mechanism, the supporting frame being shown in section. Fig. 4 represents a side elevation of Fig. 3, the driving-pulley and its support being removed. Fig. 5 represents a sectional view on line 5—5 of Fig. 4, showing the indexing tripping mechanism. Fig. 6 represents a section on line 6—6 of Fig. 2. Fig. 7 represents a sectional plan on line 7—7 of Fig. 5. Fig. 8 represents a section on line 8—8 of Fig. 2. Fig. 9 represents a section on line 9—9 of Fig. 2. Fig. 10 represents a side elevation of a part of the mechanism shown in Fig. 9. Fig. 11 represents a section on line 11—11 of Fig. 9. Fig. 12 represents a side elevation of a portion of

the parts shown in Fig. 9. Fig. 13 represents a section on line 13—13 of Fig. 9. Fig. 14 represents a section on line 14—14 of Fig. 9. Fig. 15 represents a section on line 15—15 of Fig. 9. Fig. 16 represents a section on line 16—16 of Fig. 10. Fig. 17 represents one form of index-controlling cam. Fig. 18 represents a view similar to Fig. 2, showing different connections for setting the indexing mechanism in operation. Fig. 19 represents an elevation of the timing disk for disconnecting the clutch of the indexing mechanism. Fig. 20 represents an elevation as seen from the left of Fig. 19. Fig. 21 represents a section on line 21—21 of Fig. 19. Fig. 22 represents an elevation of the timing disk with the shield removed.

The same reference characters indicate the same parts in all the figures.

10 represents the bed of a gear-cutting machine upon which is supported a cutter carriage 11 which is reciprocated on longitudinal guides of the bed. The carriage 11 has bearings in which is supported the rotatable cutter shaft 12 carrying a cutter 13.

The cutter carriage is reciprocated by means of an ordinary feed screw, the end of which is journaled in bearings within a fixed casing 14. On the feed screw within the casing are loosely mounted the carriage-feeding worm-wheel 15 and the retracting gear 16, which are separated from each other by a space occupied by a sliding clutch member 17. The latter is engaged with the feed screw so as to slide longitudinally thereon, being held from relative rotation, and it has on opposite sides, provisions for clutching engagement with both the worm-wheel 15 and the gear 16.

The gear 15 is driven at a slow speed and the gear 16 at a more rapid rate from the main drive shaft 18 which carries a belt pulley 19, whereby power is furnished the machine. The main shaft carries a bevel gear 20 which meshes with a complementary gear 21 on a shaft 22 extending longitudinally of the machine. This shaft also carries a second bevel gear 23 meshing with a gear 24 on a transverse shaft 25. Also fixed upon the transverse shaft 25 is a spur gear 26 (shown in dotted lines in Fig. 2) meshing with an intermediate gear 27, the shaft of which carries a pinion for driving another gear 28. Upon the shaft 29 of the latter is fixed a worm 30 which meshes with and so drives the 110

worm-gear 15. Gear 16 is driven by an intermediate spur gear 31 which meshes with a gear 32 fixed upon shaft 22.

The sliding clutch member is shifted by a 5 shipping lever 33 connected to one end of a rod 34 which is mounted to slide longitudinally of the machine in fixed guides 35 and is reciprocated by the cutter carriage 11 through a projection 36 on the latter engaging alternately with dogs 37 38 fixed to the rod. At the conclusion of the forward cutting stroke, the projection 36 on the cutter carriage strikes one of the dogs and moves the rod 34 in a direction to connect the 10 clutch with the return gear 16, while at the conclusion of the reverse stroke the other dog is engaged and the rod moved in the opposite direction to connect the slow-speed forward-driving gear with the feed screw.

20 The rod 34 is made in two sections having a lost-motion connection between them so that an initial movement of the right-hand section of the rod is permitted before the left-hand section is moved to operate the 25 clutch shipper in such a way as to throw in the forward-driving gear. This lost-motion connection consists of a sleeve 39 pinned to the left-hand section of the rod within which is telescopically movable a head 40 on the 30 end of the right-hand section of the rod. There is an internal shoulder at the open end of the sleeve so that the right-hand section of the rod cannot be withdrawn therefrom. The object of this lost-motion of the right- 35 hand portion of the rod is to permit the indexing mechanism to be set into operation and to complete the feeding of the gear blank before the cutter is started upon its next cutting movement.

40 In Fig. 1, a fragment of the gear blank is represented by 41 and is supported by a shaft 42 mounted to rotate in a bearing 43 which is adjustable up and down on vertical guideways 44 whereby blanks of different diameters may be brought into operative 45 relation with the cutter. In order to rotate the blank there is provided an index-wheel 45 which is a worm wheel rotated by a worm 46 meshing therewith. This worm is carried in a casing 47 which is movable up and down with the bearing 43 and so is retained always in mesh with the index wheel. The worm is rotated by a vertical shaft 48 which is so connected as to permit relative longitudinal 50 motion of the worm.

The indexing driving shaft 48 is driven from the main shaft 18 by a gear train consisting of a pinion 49 fixed to the main shaft, a spur gear 50 in mesh therewith and driven 55 thereby, a pinion 51 fixed to the pinion 50 so as to move therewith, and a gear 52 meshing with the pinion 51. This train of gears constitutes a driving train which is normally in continuous operation. The rest 60 of the intermediate gearing for rotating the

blank consists of a gear train which is only intermittently engaged with the driving train and may be referred to as the index train. This consists of a bevel gear 53 on shaft 48, a coöperating bevel gear 54 on a 70 shaft 55 extending across the machine, a gear 56 on the last-named shaft, change gears 57 58 connected together and loosely mounted on a stud 59, the former of said gears being in mesh with gear 56, and the 75 other with a change gear 60 on a second transverse shaft 61 parallel with shaft 55, a gear 62 fixed to the front end of shaft 61, and finally a gear 63 in mesh with 62. The gears 52 and 63 are rigidly connected to complementary clutch members 64 and 65 respectively, which are normally kept separated but may be brought into connection when it is necessary to feed the blank to cut another tooth. The first gear train may 80 conveniently be called the "driving means", the second train the "feeding means", and the clutch members "coupling devices", by which the respective trains may be connected to index the blank.

90 In order to permit connection of the clutch, the gear 63 to which is connected the clutch member 65, is loosely mounted upon a tubular stud 66 so as to be rotatable and movable longitudinally thereon. Within the bore of 95 the tubular stud is mounted an endwise movable shaft 67 to which the gear and clutch member are connected by a transverse pin 68 crossing the shaft and clutch. This endwise movable shaft is made of two sections 100 of which the left-hand section 67^a is mounted in a bushing 69 held in the end of a rigid arm 70 which projects forward from the frame of the machine. The bushing is held from rotation in the arm by a key 71 and is clamped 105 by nuts 72, while the shaft section 67^a is also prevented from rotating, while being permitted to move longitudinally, by a feather 73 entering a slot in the bushing. Surrounding the shaft section 67^a and held against 110 axial movement in the bushing is a sleeve 74 which engages shoulders in the bushing. Fixed to the sleeve is a pinion 75 by which it may be rotated, and the sleeve is provided with one or more cam slots 76 into which 115 project the end or ends of a pin 77 mounted transversely of the shaft section 67^a. The two sections of the shaft 67 are connected together by means of a headed axial stem 78 on one section which is placed in a shoudered socket 79 in the other section. This causes the endwise movement of one shaft section to move the other similarly, but permits the rotatable shaft section to turn relatively to the other section. It will be evident that when sleeve 74 is turned in one 125 direction, its inclined cam slots cause shaft 67 to be moved so as to bring gear 63 and clutch member 65 into engagement with the other clutch member 64, and thereby the 130

driving and index trains, which together make up the indexing mechanism, are connected and the gear blank is actuated.

It will be noted that the nuts 72 which are threaded outside the bushing 69 on opposite sides of the bracket arm 70 will enable an adjustment of the bushing longitudinally of its axis through the distance permitted by the width of key 71. Such axial movement 10 is communicated to the sleeve 74 by the shoulders on the bushing, which embrace it, and from the sleeve through the pin 77, shaft 67, and pin 68 to the clutch member 65. Thereby the distance between the clutch 15 members may be adjusted to regulate the time at which they are disconnected, and to make the time of disconnection coincide with the instant at which the shoulder 98 herein-after described, strikes the detent 96.

20 The pinion 75 is oscillated to turn the sleeve by means of an arm 80 which carries a gear segment 81 meshing with said pinion 75. The arm is rigidly connected to a hub 82 mounted loosely upon a stud 83, and to 25 the hub there is connected a second arm 84 to which is pinned a link 85 connected with a bell-crank lever 86 by means of an intermediate link or floating bell-crank 87. The bell-crank 86 is pivoted at 88 and carries 30 upon one of its arms a pin 89 projecting into the path of a dog or pawl 90 on the rod 34. Both the pin and pawl are beveled on one side so that the latter may slide over the end of the former when the carriage makes its 35 forward cutting movement, but they have cooperating shoulders which engage when the carriage is reversed and cause the bell-crank to be thrown over. The intermediate link or floating bell-crank 87 is pivotally connected at 91 with the bell-crank 86, this pivotal connection constituting the fulcrum which is moved when the first bell-crank is oscillated. The member 87 has a laterally-projecting arm or finger 92 which is also 40 moved bodily when the lever 86 is oscillated and in the path of which is a stop pin 93 which is engaged by the finger 92 when the member 87 has been moved a certain amount. The projection 92 being arrested while the 45 pivot 91 continues to move, causes the bell-crank 87 to be turned in left-hand rotation about the pin 91.

94 is a gear which meshes with gear 63 and it has a cam groove 95 into which projects a 50 detent or locking finger 96 upon the arm 84. The groove 95 is concentrically arranged on the gear throughout the greater portion of its extent but is widened at 97 and formed with a locking shoulder 98. The driving 55 mechanism tends to turn gear 94 in the direction of the arrow in Figs. 2 and 5, so when the detent on arm 84 is in engagement with shoulder 98 such tendency is resisted and the indexing mechanism is held locked. In 60 mesh with and driven by gear 94 is an inter-

mediate gear 99, to which is fixed a pinion 100 meshing with a gear 101 on the shaft 102 of which is fixed a disk 103. The disk has one or more notches 104 in its periphery, into which may extend a projection 105 on 70 the link 85. One side of each notch is formed as an abrupt shoulder which bears against a corresponding shoulder on projection 105, and when the disk is being moved, pushes link 85 to the right and thereby tends 75 to move and hold arm 84 in the widened part of cam 95 and in engagement with the locking shoulder 98.

When the locking arm 84 is so held the clutch-operating arm 80 is in the position 80 which causes the clutch members 64 and 65 to be separated. Now when the bell-crank 86 is moved in left-hand rotation by the operating rod 34, the member 87 is first raised bodily and thereby the end of link 85 which 85 carries projection 105 is raised to disengage said projection from the disk. When its disengagement has been effected, the disk is free to be rotated and the projecting arm 92 has come into engagement with stop 93. 90 Further movement of bell-crank 86 causes the link 87 to be rotated and link 85 moved bodily endwise to the left, thereby freeing arm 84 and detent 96 from the locking shoulder 98, leaving gear 94 free to turn and simultaneously rotating gear 75 and sleeve 74. The latter part of this motion of rotation causes the pin 77 to be acted on by cam slot 76 and the shaft 67 and clutch member 65 to be moved endwise, whereby the clutch is 100 connected and the indexing train set in motion to move the gear blank the necessary amount. After the dog or pawl 90 has passed by the bell-crank, link 85 is free to fall so that its projection rests upon the periphery of disk 103. The latter has meanwhile been set in rotation and when it has turned sufficiently far to bring one of its notches adjacent the projection 105, the latter falls into the same and is engaged by the 110 shoulder at the side of the notch. Further movement of the disk moves link 85 to the left, oscillating arm 80 and sleeve 74 in the direction to disconnect the clutch members, and at the same time moving detent 96 into 115 the enlarged part of cam groove 95. When the disconnection of the clutch has been effected, the locking shoulder 98 comes into contact with detent 96 and causes the indexing mechanism and blank to be stopped at 120 exactly the right point. The positive gearing between cam gear 94 and disk 103 is such as to bring the enlarged part of the cam groove adjacent the arm 84 when link 85 is operated by the disk. The disk may be 125 made to rotate at the same speed as the cam gear 94 or it may turn slower, and is provided with notches corresponding in number to the amount of the speed ratio. In the construction here illustrated, the speed ratio 130

is four and the notches consequently four in number, although it is to be understood that the cam may be made to turn any other desired number of times while the disk rotates 5 once, and a consequently altered number of notches will be provided.

In order that the gear 94 may make two or more complete rotations and so multiply the tooth spacing of the blank, I have provided upon the disk a shield which is adapted 10 to cover one or more of the notches of the disk. The shield is represented by 106 and has the same number of notches as the disk, which are similarly spaced. Two of 15 the notches 107 which are diametrically opposite each other are of the same width as the notches 104, while an intermediate notch 108 is twice, and the fourth notch 109 three times this width. The diameter of 20 the shield intermediate the notches is the same as that of the disk so that the peripheries of the two members constitute parts of the same cylindrical surface. When the parts are in the position shown in Fig. 25 19, all of the notches are uncovered but when the shield is moved in left-hand rotation by a distance equal to the width of one notch, the notches 107 are covered by overlapping parts of the shield and disk, while the notches 30 108 and 109 are open. A further movement of the disk in the same direction by a similar amount causes all the notches except 109 to be covered. Movement of the shield 106 in right-hand rotation from the 35 position shown in Fig. 19, will cause all the notches to be simultaneously covered. The projection 105 is of sufficient width to extend over parts of both the disk and shield and to rest upon the periphery of each. 40 Accordingly when the notches of the two members coincide, the projection will fall into them but when they are not side by side it will be held up. Thus by adjusting the shield the indexing mechanism may be 45 caused to disconnect itself after one, two or four rotations of the gear 94, or it may be caused to continue in operation indefinitely until it is manually stopped. For holding the shield in any adjusted relation, I provide 50 a pin 110 mounted in a tubular stud 111 carried by the shield and pressed by a spring 112 against the disk. A finger disk 113 permits the pin to be retracted. Holes 114 are formed in the disk spaced so as to 55 permit the pin to enter them and to hold the shield in any one of the required positions. An indicator pin 115 is mounted upon the disk and projects through a slot 116 in the shield. A scale of figures on the shield indicates 60 the adjustment and shows the number of rotations of gear 94 which will be made before the index mechanism is uncovered.

In Fig. 18 I have shown a different mechanism for throwing the indexing mechanism

into and out of connection. This consists of an arm or striker 156 which is mounted to oscillate on the driving shaft 18 and has a gear segment 154 meshing with a segment 157 formed upon an arm 158 which is connected to the same hub 82 which carries the arms 80 and 84. The striker or arm 156 projects into the path of a pivoted spring-pressed pawl 159 carried by the end of the 70 shipping rod 34. When the pawl engages 75 the striker it oscillates the latter and through the gear segments 154 157 and arm 158 moves the locking arm 84 away from the locking shoulder 98 and at the same time throws in the clutch. The cam groove 95 80 has an external eccentric surface 160 which engages the detent 96 at the end of each revolution of gear 94 and forces the locking arm over so that the detent is in position to be engaged by shoulder 98. With this construction the indexing gear train is automatically thrown out at every revolution of gear 94. 161 is a handle connected to hub 82 by which the indexing mechanism may be thrown into operation by hand. The 90 hub portion 82 in which the arms 80 and 84 are connected, is elongated and forms the journal upon which gears 50 and 51 are mounted to turn.

Fig. 17 shows a construction of the indexing 95 controlling cam 94 which has a pivoted latch 170 which is pressed outwardly by a spring plunger 171 and has a shoulder 172 which engages the detent 96 when the latter is in contact with the shoulder 98, and thus prevents the cam from turning in either direction. The latch is adapted to yield when the cam is turning before the detent engages the shoulder 98 so as to permit the detent to pass by shoulder 172.

I have found it to be of the utmost importance to have the locking shoulder arrest the indexing mechanism at almost the exact instant when the driving clutch members are disconnected. This is necessary in 110 order that the machine may be indexed by hand or by power at any speed, even such a low one that there is not sufficient momentum to turn the gearing at all after the clutch members have separated. In all other machines of this character with which I am familiar, the driving clutches for the indexing mechanism are thrown out an appreciable time before the lock which stops the mechanism comes into play, and consequently, unless the machine is driven at a certain fairly high rate of speed, the indexing mechanism will stop by its frictional resistance before the positive lock is engaged, and before the blank has been sufficiently 115 indexed. By providing the adjustment herebefore described, I am enabled to locate the movable clutch member 65 at exactly the necessary distance from the other member 120 64 to cause the separation to take place so 130

nearly at the exact time of engagement between the locking shoulder 98 and detent 96, as to cause the latter to engage, no matter how slow or how rapid the speed of the indexing gearing may be.

In the foregoing specification and in the drawings the indexing mechanism has been described and shown as applied to a machine for cutting spur teeth on a cylindrical gear blank, but it is to be understood that the mechanism is not restricted to so limited a class of machines or to this particular work, but it may be adapted to feed in a straight line or in a path other than circular a blank 10 in which indentations are to be cut, and it could also be used as a tool feed on an automatic machine tool. Thus the invention embodied in this application may be adapted without changing its essential features to 15 machines for cutting racks, or to any class of milling machine, whatever particular work the same is capable of performing, and the mechanism could be used for indexing the tool of an automatic drilling machine or in 20 any other relation where automatic indexing could be applied.

I claim:—

1. A gear-cutting machine comprising a blank-holding shaft, a reciprocating cutter-carriage having a cutter adapted to act on the blank, an indexing mechanism adapted to communicate motion to the blank-holding shaft, said mechanism including a loose driving member, and a clutch member which is 30 movable into and out of engagement with the driving member to render the indexing mechanism operative and inoperative, mechanism operated by the carriage in its backward movement for engaging the clutch member with the driving member, and positive operating means driven by the indexing mechanism, for first separating the clutch member from the driving member and then locking the indexing mechanism.

45 2. A gear-cutting machine comprising a blank-holding shaft, a reciprocating cutter-carriage having a cutter adapted to act on the blank, an indexing mechanism adapted to communicate motion to the blank-holding shaft, said mechanism including a loose driving member, and a clutch member which is 50 movable into and out of engagement with the driving member to render the indexing mechanism operative and inoperative, a locking gear meshing with a gear of the indexing mechanism and provided with a cam-groove having a locking shoulder, a detent movable into engagement with the said shoulder, and mechanism operated by a 55 backward movement of the carriage for first removing the detent from the shoulder and then moving the clutch member into engagement with the driving member, the said cam-groove having an eccentric portion 60 which is caused by the rotation of the locking

gear to move the detent to first separate the clutch member from the driving member, and then engage the detent with the shoulder of the locking gear.

3. A gear-cutting machine comprising a blank-holding shaft, an indexing mechanism to impart motion thereto, said mechanism including a loose driving member and a movable clutch member coöperating therewith, and clutch-operating mechanism including a longitudinally movable shaft to which the clutch member is affixed, a sleeve loosely mounted on said shaft and having oblique slots engaging studs on the shaft, means for confining said sleeve against endwise movement, and means for partially rotating said sleeve in opposite directions, and thereby imparting endwise movements to the shaft and clutch member for connecting the driving and clutch members together and subsequently disconnecting them.

4. A gear-cutting machine comprising a cutter carriage, a blank-holding shaft, an indexing mechanism to impart motion thereto, and including a loose driving member, and a movable clutch member coöperating therewith, a longitudinally movable shaft engaged with said clutch member, a gear loosely mounted on the said shaft and confined against movement lengthwise of the shaft, connections between said gear and shaft for imparting endwise movements from the gear to the shaft, a lever having a gear-segment engaged with said gear, a detent-arm affixed to said lever, a locking gear meshing with a member of the indexing mechanism and having a groove receiving the detent-arm, said groove having a stop-shoulder to arrest the detent, a rod reciprocated by the carriage and provided with a pawl, and an oscillatory arm or striker located in the path of said pawl and connected as described with the said lever and detent-arm, the groove of the locking gear having an eccentric portion formed to move the detent-arm and the lever connected therewith.

5. Indexing mechanism for metal-cutting machines comprising a driving gear train, a driven feeding gear train, a disconnectible coupling between said trains, an endwise movable shaft to which one of the coupling members is fixed, mechanism for moving said shaft to connect the coupling and thereby set in operation the feeding train, and means positively operated by the latter train for 115 reversely moving said mechanism and shaft to disconnect the coupling.

6. Indexing mechanism for blank-cutting machines, comprising a driving gear train, a blank-feeding gear train, a disconnectible 125 clutch between said trains, an endwise movable shaft to which one of the clutch members is fixed, mechanism for moving said shaft to connect the clutch and thereby set in operation the blank-feeding train, means 130

operated by the latter train for reversely moving said mechanism and shaft to disconnect the clutch, and a stop for arresting and locking the blank-feeding train.

- 5 7. An indexing mechanism for metal-cutting machines comprising continuously driven, and separated intermittently movable, indexing means, a clutch adapted to couple together said means, an endwise movable shaft for causing connection and disconnection of the parts of the clutch, a cam engaged to move the shaft, a carriage, and means operated in one direction by the carriage for moving the cam to connect the clutch, and in the opposite direction by said indexing means to disconnect the clutch.

8. An indexing mechanism for metal-cutting machines comprising continuously, and intermittently movable, indexing means, a clutch adapted to couple together said means, an endwise movable shaft for causing connection and disconnection of the parts of the clutch, a rotatable cam surrounding the shaft and engaged therewith to reciprocate the same, and mechanism for turning the cam oppositely for causing alternate connection and disconnection of the clutch.

9. An indexing mechanism for metal-cutting machines comprising continuously, and intermittently movable, indexing means, a clutch adapted to couple together said means, an endwise movable shaft for causing connection and disconnection of the parts of the clutch, means for preventing rotation of the shaft, a sleeve held against endwise movement surrounding the shaft and having cam surfaces engaged to reciprocate the same, and mechanism for turning said sleeve oppositely to cause alternate connection and disconnection of the clutch.

10. An indexing mechanism for metal-cutting machines comprising continuously, and intermittently movable, indexing means, a clutch adapted to couple together said means, an endwise movable shaft for causing connection and disconnection of the parts of the clutch, said shaft consisting of two sections one of which is rotatable and connected to a part of the clutch, while the other is held against rotation, a cam member engaged with the non-rotatable shaft section for reciprocating the same, and mechanism for driving the cam member oppositely to cause alternate connection and disconnection of the clutch.

11. An indexing mechanism for metal-cutting machines comprising continuously, and intermittently movable, indexing means, a clutch adapted to couple together said means, an endwise movable shaft for causing connection and disconnection of the parts of the clutch, said shaft consisting of two sections, one of which is rotatable and connected to a part of the clutch, while the other is held against rotation, an oscillatable

sleeve held against endwise movement surrounding the non-rotatable shaft section and having cam surfaces, a projection on said shaft section engaging the cam surfaces, and means for turning the sleeve in opposite directions to cause alternate connection and disconnection of the clutch.

12. An indexing mechanism for metal-cutting machines comprising driving means, driven feeding means, a clutch for connecting and disconnecting said means to advance intermittently the part being fed, connections operated by a moving part of the machine for making operative said clutch, and timing mechanism operated by the feeding means for disconnecting the clutch, including a timing disk having adjustable provisions for varying the time at which it becomes operative to disconnect the clutch.

13. An indexing mechanism for metal-cutting machines comprising driving means, driven feeding means, a clutch for connecting and disconnecting said means to advance intermittently the part to be fed, connections operated by a moving part of the machine for making operative said clutch, and a timing disk rotated by the feeding means having a shoulder arranged to engage said connections and move the same to disconnect the clutch.

14. An indexing mechanism for metal-cutting machines comprising driving means, driven feeding means, a clutch for connecting and disconnecting said means to advance intermittently the part being fed, connections operated by a moving part of the machine for making operative said clutch, and a timing device consisting of a disk driven by the feeding means and a shield adjustably connected to the disk, the disk having a shoulder arranged to engage and move said connections to disconnect the clutch, and the shield having a surface movable into position to cover the shoulder.

15. An indexing mechanism for metal-cutting machines comprising driving means, work-feeding means, a clutch for connecting and disconnecting said means to feed the work intermittently, connections operated by a moving part of the machine for making operative said clutch, and a timing device consisting of a disk driven by the work-feeding means and a shield adjustably connected to the disk, the disk having a plurality of notches arranged to engage and move said connections to disconnect the clutch, and the shield having a surface adapted to bridge over certain of the notches.

16. An indexing mechanism for gear-cutting machines comprising driving means, blank-feeding means, a clutch for connecting and disconnecting said means to feed a gear blank intermittently, a clutch-shifting device, a link connected to operate said clutch-shifting device and having a projection, a

- disk driven by the blank-feeding means having a shoulder for engaging said projection and moving the link in a direction to cause disconnection of the clutch, and connections 5 operated by a moving part of the machine for disengaging said projection from the disk and moving the link in a direction to cause connection of the clutch.
17. An indexing mechanism for gear-cutting machines comprising driving means, blank-feeding means, a clutch for connecting and disconnecting said means to feed a gear blank intermittently, a clutch-shifting device, a link connected to operate said clutch-shifting device and having a projection, a disk driven by the blank-feeding means having a shoulder for engaging said projection and moving the link in a direction to cause disconnection of the clutch, and connections 10 operated by a moving part of the machine for first lifting said projection out of engagement with the disk and then moving the link longitudinally to cause connection of the clutch.
18. An indexing mechanism for gear-cutting machines comprising driving means, blank-rotating means, a clutch for connecting and disconnecting said means to turn a gear blank intermittently, a clutch-shifting device, a link connected to operate said clutch-shifting device and having a projection, a disk driven by the blank-rotating means having a shoulder for engaging said projection and moving the link in a direction 15 to cause disconnection of the clutch, and connections operated by a moving part of the machine including a link having a lateral finger and connected to said first link, and a fixed stop in the path of said finger, for moving said projection in one direction out of engagement with the disk and then moving the first link bodily in a different direction to cause connection of the clutch.
19. An indexing mechanism for gear-cutting machines comprising driving means, blank-rotating means, a clutch for connecting and disconnecting said means to turn a gear blank intermittently, a clutch-shifting device, a link connected to operate said clutch-shifting device and having a projection, a disk driven by the blank-rotating means having a shoulder for engaging said projection and moving the link in a direction to cause disconnection of the clutch, and connections 20 operated by a moving part of the machine for disengaging said projection from the disk and moving the link in a direction to cause connection of the clutch, said connections including a bell-crank lever pivoted to a movable fulcrum and to the link and movable bodily in a direction at right angles to the link, and a fixed stop located to be engaged by one of the arms of the bell-crank in its movement.
20. In an indexing mechanism for a gear-
- blank, a clutch forming part of the mechanism for causing and interrupting motion thereof, a rotatable cam member engaged with a portion of the clutch to move the same oppositely for connecting and disconnecting the clutch, means connected to oscillate said cam member, a rotating locking shoulder driven by the indexing mechanism, and a stop movable into the path of said shoulder when the clutch is disconnected, to thereby arrest the motion of said mechanism. 70
21. In an indexing mechanism for a gear blank, a clutch forming part of the mechanism for causing and interrupting motion thereof, a rotatable cam member engaged with a portion of the clutch to move the same oppositely for connecting and disconnecting the clutch, an arm connected to oscillate said cam member, a rotating locking shoulder driven by the indexing mechanism, and a stop connected to be moved into the path of said shoulder when the clutch is disconnected, to thereby arrest the motion of said mechanism. 75
22. In an indexing mechanism of the character described, in combination, driving and driven indexing gear trains, disconnectible clutch members for putting said driven train in operation, a stop for arresting said driven train upon disconnection of the clutch members, and means for adjusting one of said clutch members toward or from the other, whereby the disconnection thereof may be accomplished substantially simultaneously with the action of the stop. 80
23. In an indexing mechanism of the character described, in combination, driving and driven indexing gear trains, disconnectible clutch members for putting said driven train in operation, a stop for arresting said driven train upon disconnection of the clutch members, an endwise-movable shaft section for causing connection and disconnection of the clutch members, and adjusting means for shifting said shaft to vary the distance between the members when disconnected, whereby the time of disconnection may be caused to coincide nearly with the action of the stop. 100
24. In an indexing mechanism of the character described, in combination, driving and driven indexing gear trains, disconnectible clutch members for putting said driven train in operation, a stop for arresting said driven train upon disconnection of the clutch members, an endwise-movable shaft section for causing connection and disconnection of the clutch members, a sleeve surrounding said shaft having a cam slot, a projection extending from the shaft into such slot by 115 which rotation of the cam produces endwise movement of the shaft, and means for adjusting said sleeve endwise, whereby the relative positions and time of disconnection of said members may be regulated. 120
- 130

25. In an indexing mechanism of the character described, in combination, driving and driven indexing gear trains, disconnectible clutch members for putting said driven train in operation, a stop for arresting said driven train upon disconnection of the clutch members, an endwise-movable shaft section for causing connection and disconnection of the clutch members, a sleeve surrounding said shaft having a cam slot, a projection extending from the shaft into such slot by which rotation of the cam produces endwise movement of the shaft, an externally threaded bushing surrounding and embrac-

ing the sleeve, a bracket in which said bushing is held, and adjusting collars threaded on the bushing and engaging opposite sides of the bracket, whereby the bushing, slot and shaft may be axially shifted to vary the distance between the clutch members and regulate their time of disconnection. 15 20

In testimony whereof I have affixed my signature, in presence of two witnesses.

ERNEST J. FLATHER.
